ATTORNEY.

UNITED STATES PATENT OFFICE

2,153,899

INTERNAL COMBUSTION MOTOR

Arthur B. Shover, Des Moines, Iowa

Application March 10, 1937, Serial No. 130,016

1 Claim. (Cl. 123—51)

The principal object of my invention is to provide an internal combustion motor having two pistons opposing each other in a common bore and actuated in time sequence.

5 A further object of this invention is to provide an internal combustion motor utilizing two opposing pistons driven at varying velocities and coupled together for increasing the speed of peak compression within the motor.

10 A still further object of my invention is to provide an internal combustion motor having two opposing pistons in the same bore that has no dead center and which utilizes a cam actuated by one of the pistons for obtaining the desired peak compression.

15 A still further object of my invention is to provide an internal combustion motor that is economical in manufacture, durable and efficient in use.

20 These and other objects will be apparent to those skilled in the art.

My invention consists in the construction, arrangement and combination of the various parts of the device, whereby the objects contemplated 25 are attained as hereinafter more fully set forth, pointed out in my claim and illustrated in the accompanying drawing, in which:

Fig. 1 is an end sectional view of my complete motor and its actuating means.

30 Fig. 2 is an enlarged side sectional view showing the drive mechanism between the piston driven cam and the crank shaft.

Fig. 3 is an enlarged side sectional view of the guide roller and cam and more fully illustrating its construction.

Fig. 4 is a view of a modified type of cam track.

There are many types of internal combustion motors now in use. These operate generally with a single piston which actuates a crank shaft as 40 is generally known. These motors compress against a solid head where they are ignited by an ignition means or by the heat of compression. These motors having a single piston operating in a bore induce considerable vibration into the

45 mechanism due to their rate of reciprocation, and are apt to become stuck on dead center. Furthermore, they are not flexible enough in their delivery of power to the crank shaft. I have overcome such disadvantages as will be appreciated and as hereinafter more fully set forth.

50 Referring to the drawing, I have used the numeral 10 to designate the block of my internal combustion motor having the cylinder or bore 11 and the usual crank case formed on its lower end. The numeral 12 designates a housing

formed on the upper end of the block 10 as shown in the drawing. The numeral 13 designates an ordinary crank shaft having the crank arm 14 to which is secured one end of a connecting rod 15 in the usual manner. The upper end of this 5 connecting rod 15 is pivotally secured in the ordinary way to a piston 16 which reciprocates within the bore 11, driving the crank arm 14 for rotating the crank shaft 13. Rotatably mounted in the housing 12 is a shaft 17. The numeral 18 10 designates a cam plate rigidly secured to the shaft 17 above the approximate center of the bore 11. This cam plate has an eccentric track 19 cut in one of its face surfaces. The numeral 20 designates a connecting rod having a roller 21 rotat- 15 ably secured at right angles to its upper end for engaging the slot 19. Permanently secured adjacent the upper end of the connecting rod 20 is an arm 22 to which is rotatably secured a vertical roller 23 for contacting the rear face of the cam 20 18 holding it in alignment.

The other end of the connecting rod 20 is rigidly secured to a piston 24 which reciprocates within the upper end of the bore 11. As will be noted with reference to the drawing, the block 25 10 is split in the middle and secured by bolts or like, leaving chambers 25 and 26 in communication with the central portion of the bore 11 between the pistons 16 and 24. The chamber 25 in this particular instance is the firing chamber and 30 has placed therein the ordinary spark plug 27 as shown in the drawing which is connected into the ordinary ignition system. The chamber 26 is used for the purpose of intake and exhaust and has an ordinary overhead exhaust valve 28 and 35 the ordinary intake valve 29 as shown in the drawing. The exhaust valve 28, when open, exhausts the used gases through the exhaust pipe 30. The intake valve 29 draws gasoline through an intake manifold 31 from a carburetor or the 40 like. This intake valve 29 is actuated by the ordinary cam shaft 32 which is so geared and timed to the crank shaft as to result in the functioning of the valves in the ordinary manner.

Although I show my motor as a four cycle engine, obviously it may be a two cycle engine.

Referring to Fig. 2 of the drawing, it will be noted that rigidly secured to one end of the crank shaft 13 is a bevel gear 33, and rigidly secured to one end of the shaft 17 is a similar bevel gear 50 34. The numerals 35 and 36 designate two bearings rigidly secured to the block 10 which rotatably support a vertical shaft 37. Secured to each end of the shaft 37 are the bevel gears 38 and 39 which are in operative engagement with the 55

bevel gears 33 and 34 respectively. The numeral 40 designates another modified type of cam track that may be used in place of the cam track 19 on various types of motors requiring a different piston action.

I have used the numeral 41 to indicate the power take off or drive shaft of the motor which is rigidly secured in prolongation of the crank shaft 13.

- 10 The practical operation of my device is as follows: When the pistons 16 and 24 are in the position shown in Fig. 1, and the motor fires, the piston 16 will actuate the crankshaft 13 in the usual manner. At the same time, the piston 24 will 15 be forced upwardly, forcing the roller 21 to travel along the longer slope of the cam track 19, rotating the cam plate 18 and thus turning the shaft 17. Inasmuch as the crank shaft 13 and shaft 17 are operatively connected through the medium 20 of the gears 33, 38, the shaft 37 and the gears 39 and 34, the united applied power implied to the pistons 16 and 24 will be applied to the drive shaft 41. As the pistons 16 and 24 will also travel 25 toward each other and as a comparatively quick thrust will be applied by the cam track 19 to the piston 24, the peak of compression will be attained more quickly than would be the case in a single piston motor, thus allowing a higher compression of greater power and distributing 30 the pressure against two pistons imparting the wear induced by high compression ratios to two sets of piston rings. This high compression on the firing stroke is taken care of very rapidly by virtue of the pistons traveling away from each 35 other on the power stroke. Obviously, by arranging the cam so that its peak is slightly off the peak of the crank arm 14, there would not be a chance for the motor to stop on dead center. The double or opposed transmission of power would also reduce vibration to a decided 40 degree.

Thus I have provided an internal combustion motor of great utility and power and which ful-

fills the objects and has many advantages over the single piston motor.

Obviously, my structure may be applied to multi-cylinder motors and the same principle applied, and is of great utility in Diesel or oil burning motors which are ignited by the heat of compression.

Some changes may be made in the construction and arrangement of my improved internal combustion motor without departing from the real spirit and purpose of my invention, and it is my intention to cover by my claim any modified forms of structure or use of mechanical equivalents which may be reasonably included within its scope.

I claim:

In an internal combustion motor, a block having a bore, a rotatably mounted shaft, a crank shaft secured to said shaft, a piston slidably mounted in said bore, a means for operatively connecting said piston to said crank shaft for causing said first mentioned shaft to rotate when said piston is reciprocated, a fuel inlet passageway in said block communicating with the inside of said bore, a valve for permitting the passage of fuel through said passageway at times, an outlet passageway in said block communicating with the inside of said bore, a valve for permitting the passage of gases through said outlet passageway at times, a second rotatably mounted shaft, a means for operatively connecting said second mentioned shaft to said first mentioned shaft, a cam element on said second shaft, a second piston slidably mounted in said bore, and a means for operatively connecting said second piston to said cam element for causing said first mentioned shafts to rotate when said second piston is reciprocated; said two pistons being diametrically opposed to each other in said bore and both capable of simultaneously causing said first mentioned shaft to rotate when they are forced away from each other.

ARTHUR B. SHOVER.
